Inventor.

Christopher Blake

United States Patent Office.

CHRISTOPHER BLAKE, OF BOSTON, MASSACHUSETTS.

Design No. 4,447, dated November 1, 1870.

DESIGN FOR AN UMBRELLA-STAND.

The Schedule referred to in these Letters Patent and making part of the same.

To all whom it may concern:

Be it known that I, CHRISTOPHER BLAKE, of Boston, in the county of Suffolk and State of Massachusetts, have invented a new Design for an Umbrella-Stand, of which the following is a full, clear, and exact description, reference being had to the accompanying photographs making part of this specification, in which are represented a perspective view of an umbrella-stand with a dripping-pan of my improved design applied thereto, and a perspective view of my said pan removed from its stand.

My present design consists in a pan of rectangular form, made separate from and applied to an umbrella-stand, to receive the water which drips from an umbrella when wet and placed therein; and, also, in a rectangular rest or support for the same.

In the photographs—

A is an umbrella-stand, the upright portion, *a*, of which is supported by the base *b*, in each side of which is formed a cavity or opening, *c*, for the reception of a dripping-pan, *d*, in which to place umbrellas, a hollow

rectangular projection or rest, *e*, being provided on each side of the stand for the upper portion of the umbrellas to lean against and to hold them in an upright position.

The dripping-pans are made separate from the umbrella-stand in order that they may be readily removed therefrom to empty the water which may run into them from the wet umbrellas placed therein.

Claim.

What I claim as my invention, and desire to secure by Letters Patent, is—

The design for the pan *d* and rest *e* of an umbrella-stand, substantially as shown and described.

Witness my hand this 15th day of October, A. D. 1870.

CHRISTOPHER BLAKE.
